MACHINE FOR BENDING BARS AND
THE LIKE

Ralph M. Shaw, Jr., Edgewater Park, N. J.

Application February 27, 1943, Serial No. 477,345

2 Claims. (Cl. 153—46)

This invention relates to methods of bending bars of metal or other ductile materials of unsymmetrical section and also to machines adapted for the purpose.

With pre-existent apparatus or machines it has been impossible to bend bars of the kind referred to without distortion of the cross section of the bars at the regions of bending. There are, in certain unsymmetrical shapes, such as structural angles and Z-bars, two or more axes about which rotation can be effected. Of these axes there is one whereof the section modulus is always a minimum. Unless restrained, bending always takes place about this axis regardless of the direction in which the bending force is applied. In structural angles and Z-bars this is commonly known as the "2-2 axis." When not restrained, a piece upon which the bending force is applied along the first mentioned or the "1-1 axis," but is permitted to bend along the "2-2 axis," results in a section the plane of the heel of which is non-coincident with the heel plane of the unbent section, the piece being thus distorted and weakened at the bend.

My invention is directed toward overcoming the foregoing drawback, that is to say, toward making possible the bending of bars of different cross sections in one direction or another to the exclusion of any cross sectional deformation or weakening in any part of the finished product.

This desideratum I attain in practice as hereinafter more fully disclosed, through provision of an improved machine which performs the step of fore-distorting the opposite end portions of the bars beyond the intermediate regions at which the bends are to be made in order that the tendency toward distortion at such intermediate regions is automatically compensated for during the bending, with incidental restoration of said end portions to their original condition; and through the further provision of a machine or apparatus having improved appurtenances whereby the pre-distorted end portions of the bars are held in restraint with capacity, however, to gradually assume their original relationship with respect to each other and the intermediate portions as the bending proceeds.

Other objects and attendant advantages will appear from the following description of the accompanying drawing, wherein

Fig. 1 is a view in top plan, of a machine suitable to carrying out my improved method in bending angle bars toe-inward.

Fig. 2 is a view similar to Fig. 1 showing the

relation of parts of the machine after the completion of a bending operation.

Fig. 3 is a fragmentary sectional view taken as indicated by the angled arrows III—III in Fig. 2 and drawn to a larger scale.

Fig. 4 is a detail sectional view taken as indicated by the angled arrows IV—IV in Figs. 1 and 3 and likewise drawn to larger scale.

Fig. 5 is a view corresponding to Fig. 3 with the machine arranged for bending angle bars toe-outward; and

Fig. 6 is a detail sectional view taken as indicated by the angled arrows VI—VI in Fig. 5.

The bending machine herein illustrated is generally similar to the one disclosed in U. S. Patent No. 2,266,912 granted to me on December 23, 1941, in that it comprises a bed plate 1, and a concentric circular disc 2 which is recessed into and rotatively supported by said bed plate. As shown, the disc 2 is provided at its edge with gear teeth 3 for meshing engagement with a driving pinion 4 which is similarly recessed into the bed plate 1, and which may be rotated either by manual means or by power, as desired. Rigidly secured by bolts 5 to the disc 2 at the center is a round spool-like die member 6 whereof the periphery, see Fig. 3, is profiled to snugly receive and support the horizontal flange of the angle bar B which is to be bent, and to provide a butressing surface for the upright flange of such bar. Cooperative with the die member 6 is an opposing complementary die element 7 which fits between the upper and lower flanges of said die member, and which is held against the outer face 35 of the upright flange of the angle bar B by a roller 8, said roller being adjustable in a radial guide 9 on the disc 2 in the same manner as the corresponding roller in the patent hereinbefore referred to. Attached by bolts 10 to the bed 1 and overlying the disc 2, is an inwardly projecting segmental plate bracket 11 that supports a holder 12 which is of right-angle cross sectional configuration as shown in Fig. 4 and which is formed with a hook 13 to engage over the top 40 edge of the vertical flange of one end portion of the bar B. Extending laterally from the holder 12 are studs 14 which fit into socket holes in one edge of the segmental plate 11. In turn mounted on the disc 2 is a generally similar hooked holder 16 which has pendent studs 17 fitting socket holes in said disc.

To bend the angle bar B toe-inwards, in accordance with my invention, the procedure is as follows: The bar is placed in the machine as shown in Fig. 1 with its mid portion, i. e., that

portion at which the bend is to be made, engaged in the periphery of the die member 6. The co-operative die element 7 is then slid into the interval between the back face of the upright flange of the bar and the roller 8, and the opposite end portions of said bar incidentally engaged in the hooked stops 12 and 16. Thereupon, by means of a lever or other suitable tool, the end portions of the bar B are torsionally deformed or twisted relative to the intermediate portion, both in the same direction, to an angular position such as shown in Fig. 4. With the foregoing preparation, the disc 2 is rotated in the direction of the arrow in Fig. 1 and the right-hand end portion of the bar caused to swing around the die member 6 under the pushing action of the complementary die element 7. During the bending, the pre-deformed end portions of the bar are held in restraint by the holders 12 and 16 with capacity however to turn and at the same time shift longitudinally therein, the twists being progressively absorbed in compensating for the strains induced in the metal of the bar at the region of bending. As a consequence, at the completion of the operation when the bar has been bent to the desired extent, its end portions will have assumed their original aligned relationship with the bent portion thereof, while the cross section of the latter portion will be maintained as a true right-angle. The degree of twist originally placed in the bar ends will of course have to be varied in practice in accordance with the length of the bar and the extent to which the bar is to be bent, and also in accordance with the cross sectional dimensions of the bar material. If found to be more convenient in practice, the end pre-twisting may be done before the bar is placed in the machine.

In Fig. 5 the central die member 6a is shaped to receive within its peripheral groove, an angle bar B toe-outward with the vertical web thereof backed by the mid portion of said member, and the horizontal flange thereof supported from beneath substantially throughout its width. The cooperative die element 7a, on the other hand, snugly engages between the upright flange of the central die member 6a and the top surface of the horizontal flange of the bar B. The holders used with the machine as arranged in Fig. 5 are

shaped as instanced in Fig. 6, and before bending, the end portions of the bar are twisted in the direction shown in the last mentioned illustration. The bending procedure here is exactly the same as described in connection with Figs. 1-3, incident to which the tendency toward distortion at the region of bending is compensated for by the pre-twisting of the bar ends in the indicated direction.

While for the purposes of exemplification herein, I have shown and described the bending of angle bars with my improved machine, my invention is not confined to operation on such shapes, since through suitable modifications within the scope of the appended claims, bars of other unsymmetrical cross sectional configurations can be as readily bent without sacrifice of any of the advantages hereinbefore pointed out.

Having thus described my invention, I claim:

1. A machine for bending bars of angular cross section, previously prepared by having their ends twisted relative to the intermediate portions at which the bends are to be made, comprising a pair of cooperative die members whereof one is spool-like and stationary while the other is rotatively movable thereabout, said members jointly providing a confining interval accurately conformative with the cross section of the bar; and a pair of hold-down elements associated with the die members each embodying a hook, one of said elements being rigidly mounted and the other radially adjustable and respectively engaging the pre-twisted end portions of the bar to be bent, so that incidental to the bending operation all portions of said bar will be turned back into normal position, and be free from twist.

2. The invention according to claim 1, in which the stationary spool-like die member has a circumferential groove profiled to receive the vertical and horizontal legs of the angle bar; in which the roller die member engages the back face of the vertical flange of the angle bar to confine the cross section of the latter; and in which the hold-down elements have the form of angular clips with their vertical legs turned inwardly and downwardly to hook over the top edges of the bar ends.
